SIDE SEAM FOR METAL CAN BODIES

William F. Punte, Syracuse, N. Y., assignor to
Continental Can Company, Inc., New York,
N. Y., a corporation of New York

Application August 12, 1935, Serial No. 35,864

1 Claim. (Cl. 220—76)

The invention relates to new and useful improvements in metal can bodies and more particularly to the interlocking parts of the side seam.

5 An object of the invention is to provide a side seam wherein the edges of the body blank are united by alternately disposed hook section and lap section so constructed that the raw edges of the metal in the lap sections are concealed within 10 the side seam.

A further object of the invention is to provide a side seam of the above type wherein the metal parts forming the side seam are so constructed that the seam as viewed from the outside is uniform throughout the entire length thereof.

15 A still further object of the invention is to provide a side seam of the above type wherein the edge portions of the lap section are so disposed as to mechanically resist the shearing strain on 20 the solder bond in said lap sections.

In the drawing—

Figure 1 is a plan view of a body blank embodying the improvements;

Figure 2 is a view from the inside of the can of 25 the body blank before the hooks are joined;

Figure 3 is a view similar to Fig. 2, with the hooks interlocked and the seam bumped and solder bonded;

Figure 4 is a sectional view on the line 4—4 of 30 Fig. 3;

Figure 5 is a sectional view on the line 5—5 of Fig. 3.

In the carrying out of the invention a body blank of suitable size to form a single can body 35 is cut from sheet metal after which it is notched and the edges shaped for joining. In Figure 1 of the drawing such a body blank is indicated at 1.

At the right of this figure the edge portion is slit at 2, 2, adjacent each end to provide the 40 lap sections 3, 3 which are of the usual character. At spaced intervals the edge portion is cut away as indicated at 4, 4. The ends of the cut-away portions are disposed at right angles to the edge of the blank and the inner side is parallel 45 to said edge. This edge portion is folded back along the broken line a—a to provide hooks 5, 5, see Figs. 1, 2, and 5. The portions of the body blank between the hooks 5, 5 are also folded back and form abutment members indicated at 6, 6.

50 Figures 1, 2, and 5. These abutment members are substantially half the length of the hooks 5, 5, transversely of the side seam and are preferably considerably wider than the hooks longitudinally of the side seam.

The other edge portion of the body blank is

notched at 7, 7, and folded back along the line b—b to form hooks 8, 8, and abutment members 9, 9. The hooks 8, 8 and members 9, 9, are proportioned the same as the hooks 5, 5 and members 6, 6, respectively. When the edges of the body blank are joined, the hooks 5, 5 and 8, 8, interlock as shown in Figure 5, while the members 6, 6, and 9, 9, abut as shown in Figure 4. The bumping irons are preferably so shaped that the body portion carrying the abutment members 6, 6, is forced outwardly as indicated in Fig. 4 and by the shade lines in Fig. 3. This brings the members 6, 6, and 9, 9, into alinement and abutting relation; while the body portion at the outside of the seam is uniform and without depression throughout its entire length.

The side seam thus formed includes hook sections which interlock in the ordinary way, and lap sections wherein the metal is folded back to provide abutment members and to conceal the raw edges of the metal. These hook sections and lap sections are relatively short and alternately arranged.

A solder bond is applied to the outside of the seam and the molten solder will flow freely by 25 capillary attraction to the uttermost parts of the side seam. Any gases forming in advance of the flowing solder will escape between the abutted ends of the lap sections and from said lap sections. Likewise, the solder will flow between the 30 ends of the abutted members and find a shorter path to the inner extremity of the side seams. The solder bond thus formed is indicated at 10 in the drawing.

Certain products when hermetically sealed in a 35 can and treated create an internal pressure which is far above the atmospheric external pressure on the can. This differential in pressure tends to bulge the can particularly in the central region. In the hook sections there is a tendency 40 of the interlocked hooks to unfold with a resulting rupture of the solder bond. The folded back portions of the lap sections are integral with the inner half of each hook and will restrain and prevent this unfolding of the hooks. This internal pressure 45 produces a shearing strain on the lap sections. The abutted end of the folded back members mechanically resist this shearing strain.

From the above it will be noted that the lap 50 sections cooperate with the hook sections in resisting the unfolding force on the side seam due to internal pressure and the hook sections cooperate with the abutted ends in resisting the shearing strain imposed upon the lap section.

It is obvious that changes can be made in the 55

proportions and shaping of the parts and also in the arrangement thereof, without departing from the spirit of the invention as set forth in the appended claim.

5 Having thus described the invention, what I claim as new and desire to secure by Letters Patent, is:

A metal can body having its edges joined by a side seam including interengaging folded back

portions which are spaced from each other lengthwise of the seam and abutted back portions between the interengaging portions, the portions of the can body in the region of the abutted folded back portions being bumped so as to contact with the folded back portions and a solder bond uniting the contacting portion throughout the entire limits of the side seam. 5
